UNITED STATES PATENT OFFICE.

HENRI GALOPIN, OF MELBOURNE, VICTORIA, AUSTRALIA.

MECHANISM FOR AUTOMATICALLY DISTRIBUTING LIQUID FUEL.

No. 809,438.

Specification of Letters Patent.

Patented Jan. 9, 1906.

Application filed May 19, 1905. Serial No. 261,280.

To all whom it may concern:

Be it known that I, HENRI GALOPIN, a subject of the King of Great Britain, and a resident of Chancery Lane, Melbourne, in the 5 State of Victoria, Commonwealth of Australia, have invented a certain new and useful Improved Mechanism for Automatically Distributing Liquid Fuel, of which the following is a specification.

10 My invention while applicable to any liquid relates more particularly to the distribution of liquid fuel for the purposes of lighting, heating, and the like. For simplicity I will refer to the liquid as "kerosene," although 15 my invention may be employed for other liquids for similar purposes.

The object of my invention is to provide a simple automatic mechanism which will secure the delivery to the lamp, stove, or other 20 point of consumption of a regulated supply of kerosene in such manner as to maintain the supply at a predetermined level and to prevent the supply rising above such level. I accomplish this by arranging for the kerosene to flow by gravitation through a nozzle 25 approximately conical in form, the orifice of which also forms a valve-seat. The nozzle delivers the kerosene into a chamber which contains a float having a vertical spindle. As 30 the chamber fills with kerosene such float rises, and with it the spindle rises. Such spindle contacts with a valve and in its ascent raises such valve and presses it against the valve-seat formed by the orifice of the 35 supply-nozzle, thus shutting off the flow of kerosene. As the kerosene is drawn by consumption from the chamber referred to the float and spindle will descend, thus allowing the valve to fall and the flow to resume. I 40 arrange the service-pipe from such chamber and the casing of the chamber in such a manner as to permit of the height of the chamber being adjusted vertically to suit the required level of the point of consumption at the 45 lamp, stove, or the like. I also provide an overflow arrangement which can be adjusted to suit the buoyancy of the float. I also provide a subsidiary chamber, float, and spindle to serve as an indicator of the state of 50 supply of kerosene in the reservoir. I provide a reservoir for containing the main supply of kerosene, and I arrange at the inlet end of the principal service-pipe a hand-pump to start the flow and enable the kerosene to siphon out of the reservoir without 55 requiring further attention.

In order to explain my invention more clearly, I will now refer to the drawings, which form part of this specification, where-
in—

Figure 1 represents in side elevation in a diagrammatic form the general arrangement of the mechanism. Fig. 2 is a vertical section of a portion of the mechanism. Fig. 3 is an enlarged view of the nozzle, valve, and 65 portions of the surrounding casing.

The same letters of reference indicate the same parts in all the figures.

A is a wall-bracket fixed in any convenient position in the building and supporting 70 a shelf B. Upon B is placed a reservoir C, containing the main supply of kerosene. I prefer to use for this purpose the tin or drum in which the kerosene is ordinarily purchased, perforating same for the reception of the siphon-pump D and also for an air-vent. The shelf B is arranged to be of suitable size to permit of the tin of kerosene being lifted so as to embrace or immerse D as it rises, being 75 then turned about a vertical axis and pushed 80 onto the shelf.

E is the main service-pipe, which may have one or more branches, as at E', the several branches, respectively, serving several valve mechanisms in different parts of the 85 building. At the head or inlet end of E is fixed a pump D, comprising barrel a, plunger-rod b, plunger c, gland d, and handle e. The inlet end of service-pipe is bent at f and 90 g to form a siphon.

When D has been immersed in the kerosene, the upward stroke of plunger c to its uppermost position will draw the kerosene up to the inlet h of E, and thereafter the whole contents of C will siphon out through E as fast as consumed.

Service-pipe E enters at K the small chamber F, within which is a float G, carrying a vertical spindle or rod H, passing upward within vertical pipe L, carrying at its upper 100 extremity an index-plate M. Rod H carries a pointer m, passing through a vertical slot in L.

So long as sufficient kerosene remains in C, and hence in F, to keep float G raised so long 105 will pointer m indicate to "Full" upon the index-plate; but when the supply of kerosene is exhausted float G will fall to its lowermost position and carry with it H and m, so as to indicate "Empty."

The kerosene contained in F flows downward through orifice n of nozzle N into small

connecting-chamber O and thence into main chamber P, containing a float Q, carrying a vertical spindle or rod R, the upper end of which when Q rises contacts with disk r, attached to spindle s, attached to valve S, having a valve - face t, adapted to fit against edges of orifice n. The oil passes from chamber O to tank P, between the stem s and the walls of the guide-hole in which it slides.

10 As chamber P fills with kerosene Q rises, and with it R, till by contact between R and r valve S is pressed upward against n, thus shutting off the supply of kerosene. As 15 soon as kerosene is drawn from P, Q falls slightly and S follows, thus permitting of a further inflow of kerosene into P.

V is the service-pipe leading to one or more lamps, or jets, or stoves, whose burners are all on the same level. V is arranged with a 20 bend W, so as to be to a limited extent elastic or flexible, being rigidly held to a wall or to the frame of lamp or stove, as at X. Thus while X remains a rigid connection the whole of the mechanism comprising chambers P 25 and F and their attached parts are capable of vertical adjustment. For this purpose P carries rigidly fixed to it on its exterior a preferably T-shaped slotted bracket Y with slot w, engaging with thumb-screw Z, which latter is screwed into the wall or to the frame of lamp or stove and acts when tightened up as a clamp to hold the mechanism rigid. Thus Z being loosened the whole mechanism is capable of accurate vertical adjustment of 30 height, whereupon Z is again clamped. The object of this vertical adjustment is to insure that the valve S will come into action when the level of the kerosene in the lamp or stove has risen to a predetermined level in same, 35 40 thus preventing an excessive supply of kerosene to same.

T is a T-shaped pipe attached to and emerging from chambers P, its vertical leg having at its lower extremity a plug or cork q, held 45 in place by cap y. Through y and q there passes upward a pipe p, which is capable of adjustment within T as to the level of its upper orifice. p is an overflow-pipe and leads to any convenient point of discharge. I provide 50 these arrangements for the adjustment of p in order that the overflow-level may be properly predetermined by the manufacturer, having regard to the buoyancy of float Q, which will of course vary slightly in different 55 mechanisms.

It will be found that the supply of kerosene required for a lamp or stove is somewhat greater when the flame is first lighted than when, after burning for a short time, the 60 burner becomes heated. For this reason I provide for having the buoyancy of float Q adjustable. I accomplish this preferably by placing within the chamber a weighted lever having weight a', lever-arm b', and pivot e', connected to side of chamber. Such lever-arm

has pivoted to it a rod c', passing upward through top of chamber P and embraced by a thumb - screw d'. The turning of such thumb-screw operates to draw the rod c', and hence b', upward, thus lifting the weight a' 70 off the float, thereby increasing the buoyancy of same. By these means the weight a' is allowed to rest upon float Q when the lamp or stove is first lighted, being shortly afterward raised off the float by the rotation of d'. 75

Having now described my invention, what I claim as new, and desire to secure by Letters Patent, is—

1. In mechanism for distributing liquid fuel, in combination a chamber, containing a float, such float being adjustably weighted and having a vertical spindle contacting with a vertically-moving valve, operating against the orifice of a vertical inverted conical nozzle, and arranged to shut off the flow through such nozzle when said chamber has received a predetermined charge of such liquid, and a T-shaped pipe containing an overflow-pipe capable of vertical adjustment, substantially as and for the purposes herein described. 90

2. In mechanism for distributing liquid fuel, in combination, a chamber, containing a float, such float being adjustably weighted and having a vertical spindle contacting with a vertically-moving valve, operating against the orifice of a vertical inverted conical nozzle, and arranged to shut off the flow through such nozzle when said chamber has received a predetermined charge of such liquid, a T-shaped pipe containing an overflow-pipe capable of vertical adjustment, also a registering mechanism comprising a chamber containing a float with vertical spindle carrying a pointer at its upper extremity, and moving within a vertical tube carrying an index-plate, substantially as and for the purposes herein described. 100

3. In mechanism for distributing liquid fuel in combination a chamber, containing a float, such float being adjustably weighted and having a vertical spindle contacting with a vertically-moving valve, operating against the orifice of a vertical inverted conical nozzle, and arranged to shut off the flow through such nozzle when said chamber has received a predetermined charge of such liquid, a T-shaped pipe containing an overflow-pipe capable of vertical adjustment, also a supply-pipe with a siphon-bend at its inlet end having attached a pump comprising a pump-barrel, a plunger, a plunger-rod, a gland and a handle substantially as and for the purposes herein described. 110

4. In mechanism for distributing liquid fuel, in combination, a chamber containing a float, such float being adjustably weighted and having a vertical spindle contacting with a vertically-moving valve, operating against the orifice of a vertical inverted conical nozzle, and arranged to shut off the flow through 125

such nozzle when said chamber has received a predetermined charge of such liquid, a T-shaped pipe containing an overflow-pipe capable of vertical adjustment, a registering mechanism comprising a chamber containing a float with vertical spindle carrying a pointer at its upper extremity, and moving within a vertical tube carrying an index-plate, and a supply-pipe with a siphon-bend at its inlet end having attached a pump comprising a

pump-barrel, a plunger, a plunger-rod, a gland and a handle substantially as and for the purposes herein described.

In witness whereof I have hereunto set my hand in presence of two witnesses.

HENRI GALOPIN.
